WRENCH FOR BOTTLE AND JAR TOPS

James Russell Cook, Woodbury, N. J.

Application July 3, 1944, Serial No. 543,316

1 Claim. (Cl. 81—3.42)

1

The device forming the subject matter of this specification is a wrench, adapted to be used in loosening the threaded cover of a jar or can. One object of the invention is to provide a device of the kind described which can be made cheaply out of stampings, and preferably steel stampings, the requisite strength being at the same time afforded.

A further object of the invention is to provide novel means for mounting and actuating the gripping slide, and to improve the construction of the bell crank lever which actuates the slide, novel means being provided for mounting the bell crank lever and making it readily accessible to an operator.

Within the scope of what is claimed, the structure described and shown may be changed, without departing from the spirit of the invention.

In the drawing:

Fig. 1 shows in bottom plan, a jar wrench constructed in accordance with the invention;

Fig. 2 is a longitudinal section on the line 2—2 of Fig. 1;

Fig. 3 is a transverse section on the line 3—3 of Fig. 1.

For convenience in the description of parts, that end of the wrench to which the letter A is applied will be considered the forward end, the rear end being marked by the letter B. It should be presumed that the wrench is in the position of Fig. 2, such terms as "upwardly" and "downwardly" being selected accordingly.

The handle of the wrench comprises an elongated body 1, having depending, convexed flanges 2 which are extended practically the whole length of the body. The flanges 2 reinforce the body 1 and afford an easy hand-grip. At its forward end, the body 1 is provided with a depending, convexed jaw 3, the rear edge of which is concaved and serrated as shown at 4, to acquire a good hold on the top 5 of a can or jar 6. Depending guides 7 are struck from the body 1 and are supplied with openings 8. Ahead of the foremost guide 7, the body 1 is provided with an elongated slot 9.

A slide or rack bar 10 is mounted for reciprocation in the openings 8 of the guides 7. The slide 10 is provided along one longitudinal edge with a rack 11. At its forward end, the slide 10 is provided with a broadened head or jaw 12, the forward edge of which is concaved and serrated, as shown at 14, to cooperate with the corresponding part 4 of the jaw 3 in gripping the can top 5. The upstanding post 15 of an operating projection is secured in the head 12 of the slide

2

10 and fits closely but slidably in the slot 9 of the body 1. Since the head 12 is broadened, a secure anchorage for the lower end of the post 15 is afforded. The post 15 carries a flat, transverse finger piece 16.

One of the flanges 2 of the body 1 is provided with an integral, lateral U-shaped bracket 17, in which are mounted the ends of a fulcrum pin 18.

10 A bell crank lever 19 is fulcrumed on the pin 18 within the bracket 17. The longer transverse dimension of the long arm 20 of the bell crank lever 19 is disposed at right angles to the plane in which the bell crank lever swings, and consequently a flat surface is presented to the fingers of an operator gripping the handle. The length of the short arm 23 of the bell crank lever is greater than the distance between the fulcrum member 18 and the rack 11, measured in a direction at right angles to the rack, whereby the segment 24 may be brought into and out of engagement with the rack, through the instrumentality of the long arm 20 which is located alongside the handle or body 1.

25 Adjacent to the bracket 17, the bell crank lever 19 is twisted as shown at 21, so that the forward portion 22 of the bell crank lever, and the short arm 23, are disclosed parallel to the plane in which the bell crank lever swings. This construction strengthens the mounting of the bell crank lever 19 on the fulcrum pin 18, and gives strength to the short arm 23, the short arm being provided with a segment 24, which may be brought into and out of engagement with the rack 11 on the slide 10.

30 Within the bracket 17, a spring 25 is engaged about the fulcrum pin 18, the spring engaging the bracket and the part 22 of the long arm 20 of the bell crank lever 19, to swing the arm 20 of the bell crank lever outwardly until the part 22 of the arm 20 abuts against the rear end of the bracket, the segment 24 being clear of the rack 11 on the slide 10.

35 In practical operation, the jaw 3 of the handle body 1 is engaged with the periphery of the jar top 5. By means of the finger piece 16, the slide 10 is advanced until the head 12 of the slide engages the periphery of the jar top 5. The long arm 20 of the bell crank lever 19 is swung toward the handle body 1, the segment 24 of the bell crank lever moves into engagement with the rack 11 and the slide 10, the slide is advanced, and the jar top 5 is gripped firmly between the parts 3 and 12. Lateral movement of the handle will 40 cause the top 5 to be unthreaded from the jar 6.

It will be noted that the construction is such that the entire device with the exception of the spring 25 and perhaps the post and finger piece 15-16 may be made from stampings of steel.

What is claimed is:

A jar wrench comprising a handle having a jaw and a longitudinal slot adjacent to the jaw, guides struck from the handle, a slide mounted to reciprocate in the guides and having a broad-

ened jaw overlapping the handle on opposite sides of the slot and cooperating with the jaw of the handle, an operating projection carried by the broadened jaw and movable in the slot, a lever fulcrumed on the handle, a rack carried by the slide, and a segment carried by the lever and moved thereby into and out of engagement with the rack.

JAMES RUSSELL COOK.
